UNITED STATES PATENT OFFICE.

GABRIEL KONIGSBERG, OF DENVER, COLORADO.

ORNAMENTAL STRUCTURE FOR MONUMENTS.

SPECIFICATION forming part of Letters Patent No. 393,437, dated November 27, 1888.

Application filed April 13, 1888. Serial No. 270,552. (No model.)

To all whom it may concern:

Be it known that I, GABRIEL KONIGSBERG, a citizen of the United States of America, residing at Denver, in the county of Arapahoe and State of Colorado, have invented certain new and useful Improvements in Ornamental Structures for Monuments, &c., of which the following is a specification, reference being had therein to the accompanying drawings.

10 My invention relates to an improved ornamental construction of structures adapted for use as monuments, tombstones, horse and carriage blocks, copings, &c. Its objects are to furnish such structures capable, at a moderate 15 expense or cost, of as high a degree of ornamentation as may be desired, the quality of the ornamentation being taken into account, which shall be durable in use, artistic in construction, and readily adapted for use in any 20 situation or relation where a highly-ornamental structure is desired; to which ends it consists in the features and combinations more particularly hereinafter described and claimed.

25 In practicing my invention a base or foundation or interior core is formed of a size, contour, and configuration similar to or closely approximating that to be given to the finished article or structure. Such base, foundation, 30 or interior core is then covered entirely with an ornamental surface secured thereto by cement or by any other suitable means, making a firm union between the two, the base, foundation, or interior core serving as a comparatively 35 inexpensive and economical yet lasting and firm support for such more expensive and ornamental exterior. The means for carrying this into effect may be better understood by reference to the drawings, a monumental structure being therein shown as an embodiment of the invention, in which drawings—

Figure 1 is a front view or elevation of such monument, and Fig. 2 a central vertical section thereof.

45 In the figures the reference-numeral 1 indicates the interior core, base, or foundation, formed to approximate in size and contour that

of the desired monument. It may be of any comparatively cheap rough-faced natural stone or other material having a surface to 50 which cement will readily adhere. Upon it are secured the tiles 2, the securement being by a layer, 3, of cement. These tiles may be of any desired shapes, shades, and colors, and arranged in such patterns as artistic skill and 55 taste may dictate. Among such tiles may be secured one or more plaques, 4, containing or adapted to receive pictures or inscriptions, and such plaques may be oval or may be rectangular, as shown, or of any desired shape. This 60 exterior may be further ornamented by metal traceries or frame-works 5, secured upon the tiles and containing or supporting what are termed the "roundels" or glass jewels 6, such metal traceries or frame-works being inter- 65 spersed as artistic taste may judge fit. The metal tracery also serves the purpose of aiding in retaining the ornamental covering 2 in place wherever it is applied. Such construction forms a comparatively very cheap yet 70 highly-ornamental structure, as the base or interior foundation need itself possess only firmness, and hence be of common cheap material, it serving only as a firm foundation and support for the highly-ornamental and more 75 expensive exterior.

Having thus described my invention, what I claim is—

The ornamental structure as described, consisting of a base or interior foundation of common and rough-faced material cut or molded into a shape approximating that to be given the finished article, an ornamental covering, 2, of tiles, &c., over the surface thereof and secured thereto, plaques 4, and metal tracery or framework 5, secured upon such covering and aiding, where applied, in retaining such covering, substantially as set forth.

In testimony whereof I affix my signature in presence of two witnesses.

GABRIEL KONIGSBERG.
